WINDING KEY FOR REMOVABLE CONTAINER STRIPS

Herman W. Bent, Rocky Hill, Conn.

Application May 26, 1953, Serial No. 357,475

3 Claims. (Cl. 220—52)

This invention relates to winding keys of the type adapted for removing a metal strip from a container.

Many containers, particularly those which are vacuum sealed, have sealing strips circumposed thereabout, said sealing strips having tongues engageable in the slots of manually rotatable keys, whereby to cause the strips to be broken away from their associated containers on manual rotation of the keys, to permit removal of the container lids.

One inconvenient aspect to this arrangement resides in the tendency of the wound strip to shift longitudinally of its associated winding key, out of the flat spiral or coil in which the strip should be disposed during the removing operation. When a strip deviates longitudinally of the winding key in this manner, it becomes an unmanageable spiral or helix, coiled irregularly about the shank of the key. This complicates considerably the completion of the strip-removing operation.

The main object of the present invention is to provide means on a winding key which will be particularly adapted to retain the coiled strip in a flat spiral, from beginning to end of the winding operation.

Another object is to provide means as described which, at the completion of the winding operation, will be shiftable bodily longitudinally of the key shank off one end of the key, thus to correspondingly shift the coil strip and effect complete removal of the strip from the key and allow reuse of the key.

Another object is to provide a device as described in which the means for holding the wound strip in the flat spiral will constitute a hood of U-shaped cross sectional configuration, which hood will embrace the coiled strip; a rod connected to said hood and extending in parallelism with the key shank; and a sleeve to which the rod is detachably connected, said sleeve being circumposed about the shank with the shank rotating in the sleeve.

Other objects will appear from the following description, the claims appended thereto, and from the annexed drawing, in which like reference characters designate like parts throughout the several views, wherein:

Figure 1 is a side elevational view of a winding key formed in accordance with the present invention, as it appears when in use, a container to which the key is applied being illustrated fragmentarily and in elevation;

Figure 2 is a view which shows the key shank fragmentarily and in elevation, the retaining hood being illustrated in section, the wound strip and its associated container also being shown in section;

Figure 3 is a sectional view taken substantially on line 3—3 of Figure 2;

Figure 4 is a fragmentary sectional view showing the means for connecting the rod to the shank;

Figure 5 is a transverse sectional view through the hood and shank, during the operation of winding the strip on the shank;

Figure 6 is a reduced elevational view of the shank and hood, at the beginning of the step of removing the wound strip from the shank; and

2

Figure 7 is a view similar to Figure 6 in which the hood has been shifted longitudinally of the shank for removing the wound strip from the shank.

The reference numeral 10 has been applied generally 5 in the drawing to designate a winding key formed in accordance with the present invention, said key being applicable to a sealing strip carried by a conventional container 12.

The key 10 includes a relatively elongated shank 14 10 of circular cross section, said shank being formed, at one end thereof, with a longitudinal slot 16.

The slot 16, as best shown in Figure 1, extends inwardly from one end of the shank to a location short of the mid-length point of the shank. It will be understood that a conventional sealing strip 18 will be formed at one end with a tongue, not shown, engageable in said slot for the purpose of effecting winding of the strip on the key shank responsive to rotation of the shank.

At that end thereof remote from the slot 16, the shank 20 is provided with a handle 20, which handle is adapted to be manually grasped for the purpose of rotating the shank.

In closely spaced relation to the handle 20, the shank 14 is formed with a reduced portion 22 (Figure 4), and circumposed about said reduced portion is a sleeve 24. The shank 14 rotates within the sleeve 24, the sleeve remaining stationary during the operation of removing the strip 18 from the container. At the same time, the sleeve 24, being coextensive in length with the length of the reduced portion 22, is held against movement longitudinally of the shank 14.

The sleeve 24 is provided, at one end, with an offset arm 26, said arm extending longitudinally of the shank 14 and being formed with an aperture 28 receiving the laterally projected finger 30 on one end of a rod 32. Rod 32 is extended parallel to the shank 14, and is of flexible formation, thus to permit the finger 30 to be removed from the aperture 28 when the rod is bent in the manner shown in Figure 6.

That end of the rod 32 remote from the sleeve 24 is 40 secured to a boss 34 provided upon one side wall of a hood 36 of U-shaped cross section. The hood 36, on its opposite side walls, has reinforcing plates or discs 38, said discs having openings in which the shank 14 is rotatably engaged.

In use of the device, the tongue of the strip 18 is 45 engaged in slot 16, after which the shank 14 is manually rotated. This causes the strip 18 to be wound or coiled upon the shank 14 in a flat spiral, as shown in Figures 2, 3, and 5.

The side walls of the hood 36 will be effective to 50 retain the wound strip in the flatly spiraled condition, until the strip has been completely removed from the container 12. Thereafter, the finger 30 is disengaged from the offset arm 26 in the manner shown in Figure 6, and the user, by exerting a thumb pressure against the slotted end of the shank 14 simultaneously with the exertion of an opposing pressure by the fingers against the hood 36, will cause the hood 36 to be adjusted longitudinally of the shank 14. The hood 36 is thus removed 55 bodily from the shank, and will carry with it the wound strip 18, the strip 18 falling off the end of the shank at the completion of the operation. Reuse of the key is thus permitted, it being readily apparent that one need merely return the hood 36 to its normal position, with the finger 30 engaged in aperture 28. Rod 32, of course, 60 will be of spring material, thus to permit the rod to be flexed in a manner shown in Figure 6 without danger of the rod remaining in a permanently bent condition.

The particular shape of the edges of the side walls of 65 the hood 36 is of importance, and is shown to advantage in Figures 3 and 5. The hood side walls, as shown in these figures of the drawing, are generally segmental in

shape, with rounded edge portions 40 formed thereon adjacent the intersection of the side edges of each side wall with the bight portion of the hood. These rounded edge portions shift into slidable contact with the container wall during the operation of winding said strip, the hood remaining stationary along with the rod 32 and sleeve 24 during rotation of the shank 14. The tendency of the wound strip to deviate longitudinally of the shank 14 is thus effectively precluded.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank; and a rod element secured to said guide and extending longitudinally of the shank, said rod element having one end detachably connectable to said sleeve means for normally holding the guide in the first position thereof.

2. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and

- 4
- 5 for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof.
- 10 3. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof.
- 15 4. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof, the rod element being formed of spring material tensioned to normally bias said end of the rod element into said aperture.
- 20 5. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof, the rod element being formed of spring material tensioned to normally bias said end of the rod element into said aperture.
- 25 6. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof, the rod element being formed of spring material tensioned to normally bias said end of the rod element into said aperture.
- 30 7. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof, the rod element being formed of spring material tensioned to normally bias said end of the rod element into said aperture.
- 35 8. A winding key for removing tear strips from containers, comprising: a shank slotted to receive an end of a tear strip to be coiled thereon; a guide for said strip mounted on the shank, said guide including a pair of walls fixedly connected in spaced relation and between which the strip may be coiled upon the shank, said guide being mounted on the shank for sliding movement and for rotation relative to the shank, and being shiftable between one position intermediate the ends of the shank and a second position beyond one end of the shank; sleeve means mounted on the shank for rotation relative to the shank, the shank having abutments engaging the sleeve means against movement longitudinally of the shank, said sleeve means including a sleeve element circumposed about and rotatable upon the shank and an arm having an aperture; and a rod element secured to said shank and extending longitudinally of the shank, said rod element having one end removably engageable in said aperture to hold the guide releasably in the first-named position thereof, the rod element being formed of spring material tensioned to normally bias said end of the rod element into said aperture.
